2 SHEETS—SHEET 2.

UNITED STATES PATENT OFFICE.

MARIE LENNARDS, OF CHICAGO, ILLINOIS.

DISPLAY-CABINET.

1,163,162.

Specification of Letters Patent.

Patented Dec. 7, 1915.

Application filed June 3, 1914. Serial No. 848,776.

To all whom it may concern:

Be it known that I, MARIE LENNARDS, a citizen of the United States, residing at Chicago, in the county of Cook and State of Illinois, have invented new and useful Improvements in Display-Cabinets, of which the following is a full, clear, concise, and exact description, reference being had to the accompanying drawing, forming a part of this specification.

My invention relates to improvements in display cabinets, and has for its object the production of a cabinet in which any great number of articles of merchandise may be brought into view and in such a manner that both upper and under sides of articles may be displayed at the same time.

A further object is the production of a cabinet in which a maximum number of articles may be placed in a small space and yet have all articles exhibited.

A further object is the production of a cabinet in which articles may be displayed in such a manner as to render handling unnecessary. These and such other objects as may hereinafter appear are retained by the use of my device, an embodiment of which is illustrated in the accompanying drawings, in which—

Figure 1 represents a front elevation of my improved cabinet; Fig. 2 represents a side elevation showing the arrangement of the mirrors; Fig. 3 represents a side view of one of the containers or trays; Fig. 4 represents an end view of Fig. 3; Fig. 5 shows a longitudinal inclined section of the conveying mechanism substantially on the line 5—5 of Fig. 6; Fig. 6 is a transverse vertical section substantially on the line 6—6 of Fig. 1 showing the manner in which the conveying mechanism is mounted in the cabinet; Fig. 7 represents an enlarged detail of the conveying mechanism; and Fig. 8 represents an enlarged detail of the chain and tray support.

Like references indicate like parts in the several figures of the drawings.

Referring now to the drawings, in Fig. 1 is shown a cabinet 9 capable of displaying, at one time, the contents of three boxes or trays of merchandise such, as for instance, shirt waists 11, the boxes being indicated by the numeral 12. The cabinet is provided with covering members 13 adapted to protect the conveying mechanism and prevent

accident to any one using the cabinet and has an open space between such covering mechanism through which the boxes or trays 12 are carried.

As shown in Fig. 1 the trays travel at an angle so that the contents may be readily examined without bending over the cabinet and, at the same time, the contents of the under-side of the boxes may be seen through the medium of reflecting mirrors. In the back of the cabinet is placed a mirror 15 while a second mirror 16 is placed within the cabinet below the bottom of the tray and at such an angle to the tray and the mirror 15 that the contents of the under-side of the tray are reflected into the mirror 15 and brought within the vision of the operator, as shown in Fig. 2.

The boxes or trays 12 may be made of wood or metal, and are shown with the top and bottom plates 17, 18 of glass and having end lugs or plates 19 and a top lug or ear 20, the function of which will be explained later.

Referring now to the box or tray moving mechanism as illustrated on Sheet 2, a motor 21 is suitably mounted within the cabinet and, on its operating shaft 22, are mounted two sets of driving sprockets 23, 24 and 23^a, 24^a in the center of the lower portion of the cabinet.

At each end of the cabinet are upper and lower shafts 25, 26 and 25^a, 26^a having mounted thereon sprockets 25^b, 26^b over which pass pairs of elevating chains 27, 27^a. The sprockets 23, 23^a also actuate the lower horizontal chains 28 which also passes over and actuates the sprockets 26^b. Close to and below the shafts 25, 25^a are shafts 29, 29^a provided with sprockets 30, 30^a, and also Geneva movement disks 31, 31^a provided with a plurality of fingers 32, while mounted on the shafts 25, 25^a is the other half of the Geneva movement disk 33, 33^a. A pair of chains 34 are actuated by the sprocket 30^a and passing over the sprockets 30, 30^a and through the guide casting 35 at the top of the cabinet. The chain 34 is provided with a plurality of lugs 36, 36 so spaced apart as to permit a single tray to enter between adjacent lugs and the chain 28 is also provided with similar lugs similarly spaced apart. Elevating chains 27 are provided with supporting plates 37 suitably spaced apart to permit a box or tray 110

to rest upon said plates, and be elevated from the lowermost to the top position the distance between the plates being a little more than the depth of the box or tray.

5 The path traveled by the opposite ends of the boxes and the limits of their up and down movement are indicated in dotted lines at 37^a in Fig. 2.

When the chain 34 is actuated by the 10 sprocket wheel 24 it, in turn, actuates the sprocket 30 and the half 31 of the Geneva movement, and when the finger 32 engages one of the teeth 38 of the other half of the Geneva movement it causes the elevating 15 chain to pass through a distance equal to the distance between adjacent plates and thus elevates the boxes intermittently with the horizontal movement of the chains 28 and 34.

20 It will be noted that during the actuation of the chains 28 the lugs 36 engage the end lugs 19 on the boxes moving them horizontally. When the end box, moving in the direction indicated by the arrows in Fig. 5, 25 reaches its extreme movement to the right it rests upon a pair of the plates 37 on the elevating chains 27. The next movement is through the sprocket wheel 24, as heretofore described, and raises the elevating chain one 30 step carrying the box or tray with it. When the box or tray has reached the top it is in position so that the lug 36 engages the ear 20 on the top of the box sliding it within the guiding casting 35. The next movement 35 of the chain carries the box along bringing it into view as shown in Fig. 1. The boxes are supported on the chains 28 in substantially the same manner as they are supported on the chains 34.

40 It is, of course, understood that the relation between the Geneva movement and the sprockets and lugs may be varied to suit any condition or any size of boxes, though, of course, after a device is arranged 45 for a certain size it is understood that such size will be used in the cabinet.

Just below the display opening in the cabinet I may, if I desire, place a reflector 39 with a plurality of electric lights, 40, 40, 50 in order to better display the goods in places where the light is bad or for use as evening light. These lights may be of any color or different colors so that the goods may be lighted with any color desired by the exhibitor.

I have shown this device with the boxes tilted in order to bring them better within the view of the shopper. There may be, of course, conditions in which the trays may 60 be moved in a horizontal plane and thus simplify materially the elevating mechanism, but the mechanism as illustrated and described may be made applicable for almost any desired movement of the trays.

65 I have not shown any method of wiring

or switch connections as it is not thought that illustrations of this portion of the device are necessary.

Referring now to the general operation and advantages of my device, it will be seen 70 that the motor may be run at any desired speed so that the boxes or trays may be caused to pass in front of the shopper at any desired speed, or can be stopped if desired to permit the shopper to carefully examine the goods in any particular tray, and that by the use of the mirrors both the top and bottom articles or the top and bottom of one article, if only one is in the tray, can be examined without handling and soiling the goods. Any suitable starting and stopping mechanism for the motor can be used so that the clerk may regulate the movement of the trays. If desired, the regulation of the movement may also be within 85 the control of the shopper so that, in the event that the shopper is of mature age or experienced, he may be permitted to start or stop the motor and thus in a sense do away with the necessity of constant attendance of the clerk, leaving such clerk free to attend to other duties or other shoppers.

It will be seen that the trays bearing the merchandise first appear from out of the cabinet at the right hand corner nearest the 90 spectator and travel in an oblique position in a straight line to the left hand corner where they disappear down into the cabinet and are carried, as heretofore described, on a horizontal chain in the bottom of the cabinet 100 across to the vertical chain on the opposite side and brought up and again into view and the operation repeated indefinitely.

By the use of this device several hundreds 105 of articles may be packed within a small space and yet all be readily accessible for inspection without the necessity of pulling out and opening numerous boxes and with the incident vexation and confusion resulting from disorderly stock. The device furthermore limits the necessity for devoting so much time to the habitual and professional shopper as their demands may be met by the movable display cabinet without monopolizing the attention of the clerks from more 110 profitable duties. The use of this device keeps the stock fresh as each article within the trays bears a stock number, and it will be unnecessary to disturb such articles as 115 fresh one can be readily obtained from the stock room.

I have shown this cabinet as comparatively small, displaying only three trays at one time. It is, of course, obvious that I 120 may make it as long as I desire and so constructed that any desired number of trays may be visible at one time. It may also be desirable, in using the cabinet in the aisle of a store, to have two series of cabinets set 125 back to back.

While I have shown a specific type of mechanism by means of which the purpose of my invention may be obtained, it is, of course, evident that other mechanisms may 5 be adapted to perform the same function and the mechanism itself simplified without in any way departing from the spirit of my invention.

I claim:

- 10 1. In a device of the class described, the combination with a cabinet having a display opening, a plurality of display boxes, means for bringing said boxes successively beneath said opening into and out of view, 15 said boxes having transparent tops and bottoms, and means whereby the top and bottom of said boxes may be viewed simultaneously whereby the display capacity of said device is increased.
- 20 2. In a device of the class described, the combination with a cabinet, of a conveyer having a portion extending longitudinally of the cabinet, a plurality of receptacles constructed so that their contents are visible 25 from opposite sides, carried by said conveyer and supported so that said contents may be seen directly from one side, and a mirror supported in said cabinet in such position that the other side of said contents 30 may be seen reflected in said mirror whereby the capacity of said conveyer for displaying articles is increased.

3. In a device of the class described, the combination with a cabinet having a display opening therein, of conveyer means within 35 said cabinet comprising a substantially horizontally traveling conveyer adjacent said opening, a substantially horizontally traveling conveyer beneath said first conveyer, and a pair of substantially vertical conveyers at 40 each end of the horizontal conveyers, said conveyer means including means for carrying receptacles and for transferring them from one conveyer to the other, and means for driving the horizontal conveyers, means 45 for causing the vertical conveyers to travel a distance different from the distance traveled by the horizontal conveyers in the same time, a plurality of receptacles constructed so that their contents are visible from opposite sides 50 carried by said conveyers and supported so that said contents may be seen directly from one side, and a mirror supported in said cabinet in such position that the other side of said contents may be seen reflected in 55 said mirror, whereby the capacity of said conveyer for displaying articles is increased.

In witness whereof, I have hereunto subscribed my name in the presence of two witnesses.

MARIE LENNARDS.
